UNITED STATES PATENT OFFICE.

LAWRENCE A. AVERA, OF TEXAS CITY, TEXAS.

SPRING.

1,116,203.

Specification of Letters Patent.

Patented Nov. 3, 1914.

Application filed January 10, 1914. Serial No. 811,468.

To all whom it may concern:

Be it known that I, LAWRENCE A. AVERA, a citizen of the United States, residing at Texas City, in the county of Galveston and

5 State of Texas, have invented new and useful Improvements in Springs, of which the following is a specification.

This invention relates to seat or bed springs and the principal object of the invention is the provision of a simple and efficient device of this character wherein all of the parts are removably connected to each other so as to be convenient and inexpensive to repair.

15 Further objects of the invention will appear as the following description is read in connection with the accompanying drawing which forms a part of this application, and in which:—

20 Figure 1 is a top plan view. Fig. 2 is a side elevation. Fig. 3 is a vertical sectional view showing on an enlarged scale a detail of the spring.

Referring more particularly to the drawing, 1 represents a plurality of supporting slats which are connected together at their ends by strips 2 which serve to hold the slats in spaced relation. Each one of the slats is provided with a plurality of perforations 3 spaced apart the required distance and having slidably seated therein the tubes 4. These tubes 3 have their lower ends engaged by the inturned terminals 5 of the spiral springs 6, each of which have their opposite terminals passed through one of the apertures in the slats 1 and engaged with the recess 7 formed in the upper side of the slat.

Removably mounted in the tubes are pins 8 carrying upon their upper ends the pressure plates 9 which are apertured in their corners, as shown at 10, to receive the connecting links 11. The pins 8 simply hold the pressure plates in position upon top of the

tubes 3 and when pressure is applied to said plates it is communicated directly to the 45 tube 3, which, sliding through the aperture in the slot, descends the spring 5.

When the device is used for a bed spring the tubes and their associated springs are spaced apart sufficiently to extend upon opposite sides of the slats of the bed and are preferably arranged in transverse and longitudinal rows, as shown. This arrangement, however, need not be carried out strictly when the spring is used for a seat, but in 55 practice has been found to be equally as efficient constructed in this manner as in any other.

What is claimed is:—

1. In a spring, a plurality of apertured 60 slats connected together in spaced relation, springs depending from the slats, supporting members passing through the apertures and springs and engaged with the latter, connected pressure plates mounted upon the 65 supporting members and means carried by the pressure plates and removably engaged with the supporting members for preventing disconnection of the pressure plates.

2. A spring comprising a plurality of 70 apertured slats connected together in spaced relation, springs passed through the apertures and depending from the slats, tubes extending through the apertures and springs and engaged with the lower end of the latter, connected pressure plates mounted upon the tubes and pins carried by the pressure plates and removably engaged with the tubes to prevent disconnection of the pressure plates from said tubes. 75

In testimony whereof I affix my signature in presence of two witnesses.

LAWRENCE A. AVERA.
